FLAT BACKED COUNTER STIFFENER FOR SHOES

John Hammond Stewart, Lynnfield, Mass.

Application June 9, 1931. Serial No. 543,102

11 Claims. (Cl. 12—66)

This invention relates to counter stiffeners for shoes, commonly called counters in the art. The final step in making such counters is to mold them between internal and external molds and fold 5 over the flange on the bottom edge. The external mold consists of two members pivoted to as to swing apart for reception of the blanks and discharge of the molded counters. The plane of division between these members is at the mid- 10 dle of the back of the counter, where the molded curvature is sharpest. In operation the back of the counter is apt to be nipped between the adjacent corners of the molds when the latter come together when exerting their molding pressure 15 and/or to be pressed into the space between them by the inner mold; and the part so nipped is squeezed into a very pronounced narrow ridge.

When such a counter is built into a shoe the ridge registers with the seam at the back of the 20 upper leather. Such seam has a substantial depth from front to rear because the adjacent edges of the right and left quarter pieces of the upper are turned inward within the line of stitches, making an inner ridge directly opposite to the 25 external ridge on the counter. The joint effect of the two ridges is to cause an unsightly bulging outward of the upper at the rearmost point.

My present object is to obviate this objectionable bulge, and I have accomplished it by 30 giving the counter a new formation. Such formation comprises a substantial flattening of the counter at the rear in a zone extending from top to bottom.

I have also devised means and methods for so flattening the counter, two of which are illustrated herein. One of such means and methods involves confining the counter in the original molding operation so that formation of a ridge 40 or fin is prevented and the desired flatness given to its outer surface, and the other involves a second operation, after a previous molding operation, by which any such ridge as may have been formed in the previous operation is obliterated and the desired flatness achieved. Such methods and means, and their equivalents, as well as the counter having the novel characteristics above mentioned, constitute the invention disclosed and claimed herein.

In the drawing illustrating these phases of the invention provided herewith,—

Fig. 1 is a perspective view of a molded counter having the objectionable ridge referred to;

Fig. 2 is a perspective view of a molded counter 55 embodying my invention;

Fig. 3 is an elevation of a shoe upper illustrating the location of the counter therein;

Fig. 4 is a fragmentary cross section enlarged, taken on line 4—4 of Fig. 3 and showing the back seam of the upper and its relation to the counter; 60

Figs. 5 and 6 are elevations of counter molds, in open and closed position, respectively, illustrating one form of means which I have invented for preventing formation of the objectionable ridge and giving the desired flattened form at 65 the rear of the counter;

Fig. 7 is an elevation illustrating an alternative means for obtaining the desired final result, which is applied to flatten the rear of the counter in a second operation. 70

In the main, the counter shown in Fig. 1 is a typical counter of the prior art having a ridge at the middle of the back. Whatever may be the difference of contour between different counters made for various sizes and styles of shoes, they 75 are all molded in substantially the same way and by substantially like means, the general principles of which are illustrated in Fig. 5. Such means comprise an inner mold 1, usually called a plug or last, around which the counter blank is bent, 80 outer molds 2 and 3 (usually called "molds"), which are made with hollow contours complementary to the form to be given the counter, and a flange plate or presser 4. In operation the molds 2 and 3 are forced with great pressure 85 against the counter blank which embraces the plug, squeezing and compressing the blank; and while the blank is thus gripped between the plug and mold with one edge projecting, the flange plate 4 is advanced to bend over the projecting 90 edge and form the flange. Various styles of counter are thus made, some with outturned flanges, but more with the flanges inturned, and the variations are provided for by appropriate design of the molding members and of the flange plate, 95 as is well understood by those skilled in the art and illustrated in prior patents. But in any case it is necessary to separate the molds for discharge of molded counters and admission of unmolded blanks, and to force them together in 100 applying molding pressure.

The molds as heretofore made have been formed with abrupt and relatively sharp corners at the locations indicated by the reference numerals 5 and 6, between their molding surfaces 105 and the faces of separation between them, which corners approach one another closely when the molds are brought together; but a wide gap is opened between them when the molds are separated. The center of the bowed counter is liable 110

to be, and usually is, entered more or less into this gap in being presented for molding, or by the pressure exerted by or toward the plug, and as the molds come together the corners pinch the superficial part of the counter blank, forming the ridge *a*. Inasmuch as the plug rises while the molds are coming together, it is impossible to avoid such pinching of the blank by the molds heretofore used unless the blank is unusually thin, or the plug is so adjusted as to apply no pressure at all on that part of the counter.

The ridge so made occupies the exact center of the bend, and is a projection from the extreme rear part of the counter when placed in a shoe. It registers with a seam 7 between the right and left quarter pieces 8 and 9 of the upper. This seam is made by stitches passed through the inturned adjacent edges of the pieces 8 and 9, and is located at the exact center of 20 the heel end of the shoe. It substantially increases the thickness of the upper at this point and, when additionally held outward by a ridge on the counter, causes an unsightly bulge and detracts greatly from the desirable appearance 25 of the shoe.

In accordance with my invention, I have produced counters in which, as shown by Fig. 2, instead of the ridge *a*, there is a flattened zone *b* on the outside at the rear. The term "flat" or "flattened" has reference only to the formation 30 of the elements circumferential of the counter, those indicated by the lines of shading at *b* in Fig. 2, and not at all to the elements extending from top to bottom, which may have any curvature as heretofore. Such flattening on the outside may be accompanied by a corresponding flattening at the inside of the counter; but it may also be associated with the same curvature as 35 heretofore on the interior surface, accomplished by a greater compression of the material of the counter at the flattened zone than at either side of such zone. Preferably the flattened zone merges smoothly with the curvature at either side of it, having no abrupt shoulders or angles.

For purposes of this description the counter 40 may be considered as consisting of a body *c* and flange *d*, the body comprising all of the counter except the flange. In comparing the relative density of compression of the flattened zone with 45 the adjacent parts of the counter, the body part alone and not the flange is taken as the basis of comparison; for the flange, being compressed by the flange plate or presser and not by the cooperation of the inner and outer molds, may have a radically different order of compression than the 50 body.

The flattening of the counter back may be accomplished simultaneously with its molding and compression elsewhere, or by a further operation 55 after molding in the old manner. For obtaining the effect in the first of these two ways, I have devised the means shown in Figs. 5 and 6. This means comprises an extension 10 on one of the outer molds, as the mold 3, which is arranged to bridge the gap between the corners 5 and 6 and to enter a suitably prepared space 11 in the other mold, as the outer molds approach one another and the inner mold or plug is raised, but before any considerable pressure has been applied to 60 the counter blank. This extension is formed with an inner surface which merges smoothly with the contours of the cavity in the mold member from which it springs, and comes into similar register with the surface of the cavity in the mold member which it enters. Such extension

may be, and is here shown as being, a plate or strip of metal welded or brazed to one of the outer mold members and bent or curved into the shape necessary to give the desired flattening effect in one direction to the counter. Such plate is preferably substantially rigid, but it may equally well be somewhat flexible, inasmuch as it is backed up and supported by the complementary mold when pressure is exerted. Its extremity may be beveled to a thin edge, whereby the necessity of an abrupt shoulder terminating the recess 11 which receives it in the mold 2 may be avoided. However, an equivalent extension may be formed by making one mold originally with a substantial integral extension and forming the other with a complementary recess to receive it.

Otherwise the outer molds, and the plug or inner mold, may be made, assembled with operating mechanisms in a counter molding machine, and cooperatively actuated in the manner heretofore known, or otherwise. In the common practice the plug is moved upward, that is toward the back of the cavity between the outer molds, and the outer molds are squeezed inwardly against the sides of the plug, the joint effect of these actions being to compress the counter throughout its body, with a substantial component of pressure exerted longitudinally through the plug on the back of the counter. The thrust of the plug is opposed by the mold extension 10 with the support of the contiguous parts of the outer molds. As the extension has bridged the gap between the outer molds before any substantial pressure has been exerted by this thrust, it effectually prevents any ridge from being formed; 110 while it flattens and more greatly compresses the rearmost zone of the counter when the maximum pressure thrust is applied.

The other mode above referred to of flattening the counter is illustrated in Fig. 7. The counter *f*, previously molded in the old way, is placed on a plug 12 which may be a counterpart of the plug mold on which it was first molded. The counter is then compressed at its rear between the plug mold and a presser mold 13, which has 120 a flat surface 14 opposite to the end of the plug mold. This action obliterates whatever ridge may have been formed in the initial molding and creates the desired flat zone at the back of the counter.

It is to be understood that the methods and means above described for producing the desired result are not necessarily an exhaustive illustration of all the means which may be used, but are rather illustrative of the principles applicable to the purpose. In so far as that phase of my invention which consists of a novel counter is concerned, I am not limited to any specific means for obtaining it; while as to the apparatus and method phases of the invention, I claim the substance thereof without limitation to the details of the results accomplished. That is, these principles may be applied to insuring the absence of a ridge in the finished counter even when not accompanied by a distinct flattening of the counter. So far as I am aware, it is novel with this invention both to provide a bridge across the central gap between the outer molds of a counter molding machine, to effect a greater compression in the middle rear zone of a counter than in the adjacent areas of its body, and also to compress the rear part of the counter in any further operation after molding, whatever may be the results achieved by so doing.

What I claim and desire to secure by Letters Patent is:

1. A shoe counter having a flattened zone at its back extending in the direction between the top and bottom edges of the counter. 5
2. A shoe counter in which the outer surface at the middle of the bowed portion is flattened circumferentially. 10
3. A shoe counter in which the outer surface at the middle of the bowed portion is flattened circumferentially in a zone of which the length is directed between the top and bottom edges. 15
4. A shoe counter having a zone at the back where the substance of the counter is more greatly compressed than adjacently in the body of the counter, in such manner that the outer surface of such zone is flattened. 20
5. A molded, compressed and flanged counter for shoes having a zone of greater compression at the rear, extending from the flanged edge toward the top edge and being substantially flat on the outside surface. 25
6. Counter molding means comprising separable outer molds and an inner mold, one of the outer molds having an extension bridging the gap between them when closed and cooperating with the inner mold to confine and compress the interposed part of a counter. 30
7. Counter molding means comprising separable outer molds and an inner mold, one of the outer molds having an extension and the other a recess to receive such extension when the molds are brought together; the extension being flat in the circumferential direction at its face which engages the counter. 35
8. Counter molding means comprising separable outer molds and an inner mold, one of the outer molds having an extension and the other a recess to receive such extension when the molds are brought together, said extension having a molding surface cooperative with the adjacent end of the inner mold and being in smooth continuity with the molding contours of the adjacent outer molds. 40
9. Counter molding means comprising an inner mold, two outer molds complemental to said inner mold separated from one another approximately on the median line of the assemblage and pivoted to swing together and apart, and means arranged to close the space between said outer molds when said molds are brought together; the molding surfaces of said molds and space closing means being in smooth continuity when in the closed together position. 45
10. Counter molding means comprising inner and outer molding instruments arranged to exert pressure on an interposed counter lengthwise thereof at the middle of the back portion, the outer molding instrument having a continuous, circumferentially flat, face crossing the middle of such back portion. 50
11. The method of treating shoe counters which consists in first molding the counter in the usual way, and then removing any ridge which may have been formed in the molding process at the rear of the counter and flattening such zone by pressure exerted on the counter at such rearmost zone. 55
